UNITED STATES PATENT OFFICE.

WOLFGANG E. SCHWARZMANN AND CHARLES M. WILD, OF SPRINGFIELD, MASSACHUSETTS, ASSIGNORS TO BOSCH MAGNETO COMPANY, A CORPORATION OF NEW YORK.

ELECTROMAGNETIC VIBRATOR.

1,211,768.

Specification of Letters Patent.

Patented Jan. 9, 1917.

Application filed August 10, 1914. Serial No. 856,042.

To all whom it may concern:

Be it known that we, WOLFGANG E. SCHWARZMANN, a citizen of the United States, residing at and whose post-office address is No. 38 Hamburg street, in the city of Springfield, county of Hampden, and State of Massachusetts, and CHARLES M. WILD, a citizen of the United States, residing at and whose post-office address is No. 14 Springfield street, in the city of Springfield, county of Hampden, and State of Massachusetts, have invented certain new and useful Improvements in Electromagnetic Vibrators; and we do hereby 10 declare the following to be a full, clear, and exact description of the invention, such as will enable others skilled in the art to which it appertains to make and use the same.

The object of the present invention is to 20 provide an improved electromagnetic vibrator suitable for use in electrical ignition systems for internal combustion engines, and particularly a vibrator for this purpose wherein the vibratory armature is capable 25 of operation at high frequency over prolonged periods without "freezing" or sticking at the contacts even when a comparatively high voltage is applied to the terminals. Although a vibrator having these 30 characteristics is of general utility in electrical ignition systems and for other purposes, yet it is particularly useful for supplying current during starting to the primary winding of a magneto to generate ignition 35 voltages in the secondary winding thereof satisfactory for producing sparks at the spark plugs to ignite the combustible mixtures present in the cylinders. By supplying interrupted currents of high frequency 40 to the magneto, the current required is proportionately reduced, thus reducing the size of the battery or other source of current for the purpose. Furthermore, by rendering the coöperative contacts safe against freezing 45 and sticking, failure to disconnect the battery immediately after the engine has started up under its own power does not introduce unreliability and failure in the succeeding starting periods. The vibrator 50 closed herein not only meets these requirements, but the construction lends itself to association with a condenser in a closed housing which not only protects the working parts from exposure and against the 55 entrance of water and dirt, but provides ac-

cess for adjustment of the vibratory armature and the coöperative contact terminals. These and other advantages will be pointed out in the following description and in the appended claims, taken in connection with 60 the accompanying drawings, in which—

Figure 1 represents a central vertical section of a preferred embodiment within our invention; Fig. 2 represents a view, mainly in section on line 2—2 of Fig. 1, but partly 65 in elevation; Fig. 3 represents a section on line 3—3 of Fig. 1; Fig. 4 represents a top view of the magnetic core particularly showing the pole pieces thereof; and Fig. 5 is a wiring diagram of the vibrator. 70

The magnetic core 1 is shuttle-shaped and comprises the cross bar 2 and the side flanges 3 integral therewith, the pole pieces 4 thereof being fastened at 5 to the side flanges and providing an air gap at 6 in the magnetic 75 circuit. The magnetizing coil 7 is wound on the cross bar, and a plate condenser 8 of circular outline with straight sides resting against the inner parts of the side flanges 3 is held between the top of the magnetizing 80 coil and the under side of the pole pieces by a bolt 9 passing through the condenser plates and through one of the pole shoes. The outer faces of the side flanges are screw-threaded at 10 for engagement with a support made up of an internally-threaded 85 brass ring 11 and a cover 12 of insulating material. The upper part of the ring is serrated at 13 so as to be lightly held against turning by the curved spring finger 14 at 90 any position to which the support may be adjusted. The continuous groove 15 is cut in the ring, and in this groove loosely sets the vibratory armature comprising the I-shaped steel diaphragm 16 and an iron button 17 bridging the gap 6 in the magnetic circuit, but normally held away from contact with the pole pieces by the spring action of the diaphragm. The button 17 is riveted to the diaphragm and a contact terminal 18 of platinum is mounted on the upper side of the rivet. A flanged brass sleeve 19 is fastened centrally of the cover 12, and a screw 20 having a platinum end 21 forming a contact terminal coöperative with the terminal 18 is screwed into the sleeve and locked in adjusted position by the nut 22. The housing base is made of aluminum and has an internally screw-threaded rim 23 100 standing from a flanged base plate 24. The 105 110

flanged disk 25 of waterproof insulating material is fastened by the screws 26 to the base plate, while the fiber disk 27 and the bottom end of the flanged sides of the magnetic core resting thereon are screwed at 28 to the disk. In this way, the bottom of the vibrator is tightly closed to the outside against the entrance of water and dust, the continuous recess 29 serving to deflect from 10 the joint of the disk 25 any water which may get underneath the base plate. The holes 30 provide for screws for fastening the vibrator to the dashboard of an automobile or other support. The steel hood 31 15 of the housing has screw threads engaging the screw threads of the upstanding rim 23 of the housing base, and is provided with a tapered locking end portion 32 designed to tightly fit a beveled seat in the upstanding 20 rim to thereby provide a water and dust tight connection between the hood and the housing base.

As shown particularly in Figs. 2 and 5, one terminal of the magnetizing coil 7 is 25 electrically connected by the wire 33 to the binding post 34, which is insulated from but fastened to the housing base. The insulated binding post 35 is electrically connected by the wire 36 to the insulated plates 30 of the condenser 8, and also by the branch wire 37 to the screw 20 carrying the contact terminal 21. The contact terminal 18 is grounded on the magnetic core through the vibrator diaphragm 16 and the ring 11, 35 while the other plates of the condenser are grounded thereon through the bolt 9 and a pole piece 4. The other end of the magnetizing coil 7 is grounded directly on the core.

40 The support carrying the vibratory armature is screwed down on the magnetic core until the proper clearance exists between the button 17 and the pole pieces 4, the spring finger 14 maintaining the adjustment. Then 45 the screw 20 is adjusted and locked in such position that the contact terminal 21 lightly engages the contact terminal 18. Now when the binding posts 34, 35, are electrically connected to a battery or other source of 50 current, the vibratory armature vibrates, alternately breaking and making the circuit of the magnetizing coil at the coöperative contact terminals 18, 21, while the condenser 8 electrically connected across those terminals suppresses the sparks thereat. The 55 springy and light weight character of the vibratory armature, together with its shape and the accuracy to which the parts may be readily adjusted and maintained in that adjustment, results in a vibratory movement of a frequency which is high compared with that of the customary types of electromagnetic vibrators. Furthermore, as a result of the loose fit existing between the vibratory 60 armature and the groove 15 of the support, 65

the vibratory armature rotates during its vibration. Freezing or sticking of the coöperative contact terminals is thereby prevented, and as a result of the uniform wear of the contact surfaces the vibrator operates 70 over prolonged periods without requiring adjustment or renewal.

It will be observed that the construction herein disclosed is well adapted for convenience in assembly and for inspection and repair. The installation or removal of the hood does not disturb any of the working parts of the vibrator, and the adjustment of the coöperative contact terminals and for the throw of the vibratory armature are 75 readily accessible when the hood is removed. Furthermore, the shuttle-shaped magnetic core provides for the compact embodiment of the condenser and magnetizing coil, and for sturdy connection to the housing. 80 85

Having thus described our invention, what we claim is:

1. In an electromagnetic vibrator, a shuttle-shaped magnetic core having a cross bar and side flanges and also having pole pieces 90 forming an air gap in the magnetic circuit, a vibratory armature bridging the air gap and carrying a contact terminal, a coöperative contact terminal, a magnetizing coil mounted on the cross bar and electrically 95 connected in circuit with the contact terminals, the side flanges of the core extending above and below the magnetizing coil, and a condenser electrically connected across the contact terminals and fastened in place between the magnetizing coil and the pole pieces. 100

2. In an electromagnetic vibrator, a magnetic core comprising a cross bar and end flanges integral therewith, pole pieces fastened at one end of the side flanges and forming an air gap in the magnetic circuit, a vibratory armature designed to bridge the air gap and carrying a contact terminal, a coöperative contact terminal, a magnetizing 105 coil mounted on the cross bar and electrically connected in circuit with the contact terminals, a condenser electrically connected across the contact terminals and fastened in place between the cross bar and pole 110 pieces, and a housing comprising a base fastened to the other ends of the side flanges of the core and a hood fastened to the base. 115

3. In an electromagnetic vibrator, an electromagnet having a magnetizing coil, a vibratory armature rotatably supported with respect to the electromagnet and carrying a contact terminal, and a coöperative contact terminal, the magnetizing coil being 120 electrically connected in circuit with the contact terminals. 125

4. In an electromagnetic vibrator, a magnetic core, a support, a vibratory armature loosely fitted to the support for vibratory and rotary movements relatively thereto, a 130

contact terminal mounted on the vibratory armature, a coöperative contact terminal fastened to the support in adjustable position relatively to the vibratory armature, 5 and a magnetizing coil electrically connected in circuit with the contact terminals.

5. In an electromagnetic vibrator, a magnetic core having pole pieces forming a gap in the magnetic circuit, a support adjustably connected to the core, a vibratory armature comprising a diaphragm connected at opposite points to the support and an iron button fastened to the diaphragm in position to bridge the gap, a contact terminal 10 carried by the vibratory armature, a coöperative contact terminal adjustably connected to the support, and a magnetizing coil electrically connected in a circuit with the contact terminals.

20 6. In an electromagnetic vibrator, a magnetic core, a support having a continuous groove, a vibratory armature loosely fitted in the groove of the support, a contact terminal carried by the vibratory armature, a coöperative contact terminal carried by the support, and a magnetizing coil connected in circuit with the contact terminals.

7. In an electromagnetic vibrator, a magnetic core, a support having a continuous 30 groove, an I-shaped vibratory armature having its end flanges loosely fitted in the groove of the support, a contact terminal carried by the vibratory armature, a coöperative contact terminal carried by the support, and a magnetizing coil connected in circuit with the contact terminals.

8. In an electromagnetic vibrator, a magnetic core having pole pieces forming a gap in the magnetic circuit, a support adjustably connected to the core and being provided with a continuous groove, a vibratory armature comprising an I-shaped dia-

phragm having its end flanges loosely fitted in the groove of the support and an iron button carried by the diaphragm in position to bridge the gap, a contact terminal mounted on the vibratory armature, a coöperative contact terminal carried in adjustable position by the support, and a magnetizing coil electrically connected in circuit with the contact terminal.

9. In an electromagnetic vibrator, a magnetic core, a vibratory armature responsive to magnetic attraction of the core and carrying a contact terminal, a coöperative contact terminal, a magnetizing coil electrically connected in circuit with the contact terminals, and a substantially watertight housing comprising a base fastened to the core and having a beveled seat and a hood in screw-threaded engagement with the base and having a tapered end portion contacting with the beveled seat to form a substantially watertight joint.

10. In an electromagnetic vibrator, a magnetic core, a vibratory armature responsive to magnetic attraction of the core and carrying a contact terminal, a coöperative contact terminal, a magnetizing coil electrically connected in circuit with the contact terminals, and a housing comprising a base portion and a hood detachably connected thereto, said base carrying an insulating support for the core and having a continuous recess in proximity to the joint with the support for deflecting water therefrom.

In testimony whereof we affix our signatures, in presence of two witnesses.
